PUMP

Finn T. Irgens, Wauwatosa, Wis., assignor to
Outboard Marine & Manufacturing Company,
Milwaukee, Wis., a corporation of Delaware

Application August 5, 1938, Serial No. 223,167

6 Claims. (Cl. 103—132)

This invention relates to improvements in pumps. It has particular reference to a pump for outboard motor usage.

It is the object of the invention to provide a novel, simplified, and inexpensive pump with a positive means of displacing the liquid pumped and yet a displacement member which will not be damaged by foreign matter in such liquid.

More particularly stated, it is proposed to provide a pump of the rotary displacement type with a gyratory piston or displacement member composed of a single piece of rubber or rubber substitute held by its own elasticity under compression in the pump chamber and sufficiently deformable in the presence of foreign matter such as pebbles or sand so as to expel such foreign matter through the pump without damage to any of the parts thereof.

It is a further object of the invention to provide a novel and improved pump chamber structure specifically designed for outboard motor usage.

In the drawing:

Fig. 1 is a fragmentary view in side elevation of a portion of the lower unit of an outboard motor having unitarily attached and incorporated therein a pump casing and pump embodying this invention.

Fig. 2 is a detail view in axial section on an enlarged scale through the pump casing portions of the outboard motor structure shown in Fig. 1.

Fig. 3 is a detail view taken in section on the line 3—3 of Fig. 2.

Fig. 4 is a detail view taken in section on the line 4—4 of Fig. 3.

Like parts are identified by the same reference characters throughout the several views.

The outboard motor lower unit 5 shown in Fig. 1 is provided internally with a gear casing 6 in which are disposed the pinion 7 and gear 8 for driving the propeller shaft 9. The general arrangement is conventional, although the gear casing 6 has been very much shortened to provide for the attachment at the rear of the outboard motor lower unit 5 of the special closure element 10 and pump casing section 11, both of elements 10 and 11 being held in assembly to the rest of the lower unit by means of the bolts 12. The sectional construction as above described enables convenient access to the gear casing 6, nevertheless leaving the pump runner unusually accessible between the casing element 11 and the closure member 10 on the outside of the packing employed for the propeller shaft 9.

The closure section 10 provides a bearing 14 and bushing 15 for the propeller shaft 9. Externally of the bushing the packing elements 16 and 17 are seated about the shaft in a recess in the sectional unit 10 as a seal to prevent the escape of grease from the gear casing and to

prevent the access of water thereto. In the upper part of unit 10 is the delivery chamber 18 of the pump from which the usual water supply pipe 19 leads to the cooling jacket of the engine.

Externally of closure section 10 shaft 9 carries an eccentric 20 which operates within a gyratory displacement piston 21 restrained against rotation by an integral lug 22 which projects from its periphery. Concentric with its bearing on the eccentric 20, the piston 21 is provided with peripheral grooves 23, these constituting a preferred means of providing for the deformation of the piston under load.

The gyratory piston 21 is preferably made of rubber or some other substitute such as Neoprene, Neoprene being preferred for the reason that it is resistant to oil. The pump casing section 11 is cup-shaped, being provided with a generally cylindrical pump chamber at 25, with a water inlet at 26 and an outlet at 27 into the chamber 20 which communicates along the upper bolt 12 with the discharge chamber 18 of the pump. One side wall of chamber 25 is provided by the section 11 and the other side wall is provided by section 10, the flexible and elastically deformable displacement body or piston 21 being confined in chamber 25 under slight pressure upon the tightening of the retaining bolts 12.

The integral lug 22 of the piston is confined between one side of the outlet port 28 and a wall 30 member 29 so that the piston cannot rotate but is free to gyrate as the eccentric 20 moves it during the rotation of the propeller shaft 9.

The opening at 30 in the pump casing section 11 through which shaft 9 projects has sufficient clearance so that the water in which the propeller 31 operates is freely admitted along the shaft to the central part of the pump chamber 25. Thus the bearing between the eccentric 20 and the hub portion of the gyratory piston 21 is water lubricated, and the bearing surfaces between the side walls of casing 25 and the side faces of the gyratory piston 21 are likewise water lubricated.

The opening 26 may be screened if desired, but it has been found that sand and even pebbles of substantial size which find their way into the opening 26 will simply embed themselves in the displacement piston 21 and pass freely with the piston in its gyratory movement until released adjacent the discharge port 27, being either deposited in the settling chamber 18 or carried upwardly through pipe 19 with the stream of water delivered by the pump. The channels 23 in the face of the piston permit the piston to be deformed by extraneous bodies more readily than would be the case if the piston were not channelled or otherwise relieved.

Thus, the structure is one which provides positive circulation of the liquid pumped, while at

the same time freely passing foreign objects which would destroy the ordinary piston circulating pump. Notwithstanding these advantages the structure is exceptionally inexpensive and 5 easy to produce and assemble.

I claim:

1. A device of the character described, comprising a casing section having a bearing face and provided with a shaft bearing opening to said 10 face and a discharge chamber likewise opening to said face, a complementary casing section provided with a bearing face opposing the face of the first mentioned section and provided with a side wall enclosing a pump chamber between said 15 bearing faces, a shaft in the shaft bearing, an eccentric on said shaft, an elastically deformable displacement piston journaled on the eccentric and confined between the opposing bearing faces of the respective sections, means connected with 20 one of said sections for restraining said piston against rotation while permitting it gyroscopic movement on said eccentric, said piston being cut away to provide relief for increasing its flexibility in the presence of a foreign body in said 25 pump chamber, said pump chamber communicating with said first mentioned chamber for the discharge of fluid pumped and being provided with an inlet for such fluid.

2. The combination with a hollow casing comprising an end wall provided with a cavity opening through said wall independent of the casing and with a bearing opening through said wall and communicating with said casing, of a shaft projecting from said casing through said bearing, an eccentric on said shaft externally of said wall, a displacement pump member operatively mounted about the eccentric to receive motion therefrom, said member bearing on said wall and being provided with a projecting tab, and a chamber element seated against said casing end wall and having a chambered portion within which said member is fitted and enclosed and having an outlet passage portion extending from said chambered portion to cover that part of said wall 45 through which said cavity opens.

3. The combination with a hollow casing comprising an end wall having a bearing opening through said wall communicating with the casing and a discharge opening through said wall, said 50 wall being provided with a discharge cavity independently of said casing and with which said discharge opening communicates, of a shaft projecting from said casing through said bearing, an eccentric on the shaft externally of the wall, a displacement pump member operatively mounted on the eccentric to receive motion therefrom, said member bearing on the wall and being provided with a projecting tab, and a chamber element seated against the casing wall and having a chambered portion within which said member is 55 fitted and enclosed, said chamber element having a discharge passage communicating through the discharge opening of the wall with the discharge cavity aforesaid and provided with means 60 engaging said tab for restricting said displacement member against rotation while permitting it to move upon the eccentric, and means for fastening said chamber element to said wall including a bolt extending through said discharge 65 passage, said discharge opening, and said cavity.

4. The combination with a hollow casing opening at its end, of a wall closure for said casing provided with a cavity independent of the casing

and also provided with a bearing opening into said casing, said wall having an outwardly disposed plane face, a shaft projecting through said bearing from said casing, an eccentric mounted on said shaft externally of said wall 5 face, a displacement pump member operatively mounted about the eccentric to receive motion therefrom, said member bearing on the wall and being provided with a radially projecting tab, a chamber element seated against the casing closure wall and having a chambered portion within which said member is fitted and enclosed, an outlet passage opening radially from said chambered portion and extending along said wall, said tab projecting into a part of said passage, means in 10 said passage engaging said tab, whereby to secure said displacement member against rotation while permitting it freedom of movement upon said eccentric, and bolts extending through said chamber element and said closure into said casing and 15 constituting means for holding said element closure and casing in assembly, one of said bolts extending through the outlet passage of said chamber element, said wall having a port affording communication between said passage and said 20 cavity and through which said bolt extends.

5. The combination with a casing having an end wall provided with a cavity opening through said wall, of a shaft projecting from the casing, an eccentric mounted on the shaft, a pump element mounted on the eccentric, a cup-shaped chamber element confining said pump element and provided with a pump chamber substantially concentric with the shaft and with an intake passage opening from the exterior and a 30 discharge passage constituting an enlargement of said chamber communicating through said wall with said cavity, partition vane means flexibly connecting said pump element and said chamber element for cutting off direct communication between said passages while accommodating orbital movement of said pump element on said eccentric, and means detachably connecting said chamber element with said casing.

6. The combination with an outboard motor gear casing having an end wall provided with an internal cavity opening through said wall, of a propeller shaft disposed within said gear casing and projecting therefrom through said wall below said cavity and opening, said wall having an 40 external face with an upwardly elongated portion above said shaft through which said cavity opens, an eccentric mounted on the shaft, a pump element mounted on the eccentric, a cup-shaped chamber element confining said pump element and provided with a pump chamber substantially concentric with the shaft and also provided with a discharge passage constituting an upward extension of said chamber into registry with the opening to said cavity, said chamber being provided with a lateral inlet passage, a flexible vane carried by said pump element and projecting into one of said passages, means in said last mentioned passage for holding said vane reciprocably at one side of the passage in a position to cut off direct communication between said passages while accommodating orbital movement of said pump element on said eccentric, and means detachably connecting said chamber element with said casing, said propeller shaft projecting beyond said chamber element from said casing.

FINN T. IRGENS.
